DUPLEX RAIL ASSEMBLY FOR LINE
CASTING MACHINES

Thomas Franklin Ellis, Topeka, Kans.

Application September 19, 1949, Serial No. 116,568

3 Claims. (Cl. 199—29)

1

This invention relates to type-setting or composing machines of the kind utilizing matrices that are assembled into justified lines, cast or molded upon a bar or slug and returned to a magazine for reuse, the primary object being to improve upon the "stick" or assembling elevator forming a part of such machines.

Those skilled in this art are familiar with the operation of machines of the above character, wherein, through use of a keyboard and its related parts, matrices are released from a magazine in the order in which the characters are desired. The released matrices are delivered to an assembling elevator or assembler provided with rails for receiving legs or ears forming part of each matrix. The assembler is conventionally provided with a pair of auxiliary or duplex rails, one of which receives the matrices in a raised or auxiliary position, the other being movable to and from a position permitting the matrices to assume a lower or regular position in alignment upon a stationary support rail.

This invention relates specifically to improvements in the above described assembler and particularly to improvements in the matrix supporting rail structure thereof, the primary object being to provide a single rail for supporting the matrices in the auxiliary position, such rail being shiftable along a pair of intersecting paths of travel, one to move the same entirely to an inoperative position, and the other to move the same to a position permitting movement of the matrices to the regular, lower rail position while maintaining previously assembled matrices in the raised position.

It is the most important object of this invention to provide rail structure as above set forth capable of permitting rapid assembly of the matrices at two different levels in the assembler whereby the operator may instantly use either character of the matrix and thereby compose a single character word, phrase or sentence in bold face type for instance, and succeeding words or phrases in regular type.

Another important object of this invention is to provide an assembler having a shiftable rail for supporting matrices in an auxiliary position and provided with an underlying actuating plate for moving the same in one direction, the rail being shiftable in another direction relative to the plate for permitting a predetermined number of matrices to move to the regular position in the assembler while the shiftable rail maintains matrices thereon in said auxiliary position.

Other objects of this invention relate to the

way in which the aforesaid plate is filled within a cavity formed in a head portion of the assembler frame; the way in which said plate is held to permit free movement of the shiftable rail relative thereto; the means of actuating the shiftable rail through use of said plate either by a finger or a foot control; and many additional, more minor objects, all of which will be made clear or become apparent as the following specification progresses.

2

In the drawings:

Fig. 1 is a front perspective view of an assembler for typesetting machines, showing a portion only of the machine itself and embodying the 15 improvements in rail assembly forming the subject matter hereof.

Fig. 2 is a fragmentary, elevational view showing a portion of the foot control therefor.

Fig. 3 is an enlarged, detailed, transverse cross- 20 sectional view taken on line III—III of Fig. 1.

Fig. 4 is a transverse cross-sectional view taken on line IV—IV of Fig. 1.

Fig. 5 is a perspective, stretched-out view showing parts of the assembler including the rail 25 structure improvement hereof; and,

Fig. 6 is an inverted plan view of the rail actuating plate per se.

In Fig. 1 of the drawings there is illustrated the conventional keyboard 10 forming a part of the 30 type-setting machine to which this invention relates. Through selective pressing of keys 12 of board 10, an operator releases desired matrices from a magazine therefor (not shown) for delivery via throat 14 to an assembler broadly designated by the numeral 16.

Assembler 16 includes a frame 18 having a horizontal head 20 that in turn is provided with a depending stem 22 fastened at its lowermost end by screw 24. Fig. 1 also illustrates the conventional backing plate 26, gate 28, and gate 40 spring 30 forming a part of the assembling elevator unit 16.

Matrices used with a machine of this character are provided with opposed lugs serving to support the same within the assembler 16 between frame 18 and backing plate 26 as the same are delivered through throat 14. Justification and distribution is automatic and the matrices are next presented to a casting mechanism (not shown) where molten metal is forced into indented characters formed on the edges of the matrices. After the matrices have been used to cast a line on a bar or slug, they are redelivered to the storage magazine therefor.

Normally the matrices are received by a rail 32

3

taking the form of an offset, elongated shoulder on the innermost face of head 20. Rail 32 co-operates with an opposed rail (not shown) on backing plate 26 in supporting the matrices and extends longitudinally along head 20 near its uppermost, horizontal face 34.

The improvement hereof includes an elongated cavity 36 formed in face 34 of head 20 having a longitudinally, elongated wall 38 parallel with rail 32 and separating the latter from cavity 36. The ends 40 of cavity 36 are spaced from the proximal ends of head 20 and are rounded as the same merge with wall 38. The bottom of cavity 36 is flat and horizontal in parallelism with shoulder or rail 32.

An elongated plate 42, complementary in shape with cavity 36, is only slightly shorter than the cavity 36 but appreciably wider as is shown in Figs. 3 and 4. Plate 42 is at least as thick as the depth of cavity 36 and is adapted to fit therewithin for transverse sliding movement on the bottom wall of cavity 36.

Superimposed upon plate 42 is a narrower, elongated, auxiliary matrix supporting rail 44. Rail 44 is longer than plate 42 and cavity 36 and has superimposed thereover a retaining bar 46. Bar 46 is held in place on head 20 by screws or the like 48 extending into face 34 of head 20 outwardly from each end respectively of cavity 36. Perforated shims or blocks 50 for each screw 48 are interposed between bar 46 and face 34 to clear rail 44.

Head 20 of frame 18 has a plurality of outwardly extending bearings 52 on the front vertical face thereof for rotatably receiving a horizontal shaft 54. Shaft 54 is in turn provided with upstanding arms 56, one of which extends downwardly into a finger 58. Arms 56 are received at their uppermost ends by openings 60 formed in plate 42 near that marginal edge thereof overlapping shaft 54. It is through actuation of finger control 58 that plate 42 is moved transversely within cavity 36 as shown by dotted lines in Fig. 3. A transverse pin 61 in at least one of the arms 56 overlies plate 42 to prevent tipping thereof.

The aforesaid marginal edge of plate 42 has a notch 62 formed therein intermediate its ends for clearing a U-shaped, downwardly facing ear 64 extending laterally from the outermost longitudinal edge of rail 44. Upwardly extending pins 66 on plate 42 extending through clearing slots 68 in rail 44 are engaged by the lower face of retaining bar 46. The latter thereby serves to hold plate 42 downwardly and thereby provides clearance for movement of rail 44 relative to plate 42. Conversely, pins 66 could obviously be placed on bar 46 and bear on plate 42 after passing through clearance spaces at openings in rail 42.

A pair of spaced spring-pressed balls 70 in head 20 and registering with cavity 36 bear on the lowermost face of plate 42. A pair of indentations 72 and 74 are formed in plate 42 for each ball 70 respectively. Indentations 72 receive balls 70 to yieldably hold plate 42 at one end of its path of travel adjacent wall 38, and indentations 74 yieldably hold plate 42 in the dotted line position of Fig. 3.

Rail 44 has a pair of legs 76 and 78 extending from the ends thereof, lug 78 receiving the matrices as the same are delivered to rail 44 and lug 76 guiding the matrices from the assembler. An L-shaped clip 80 on lug 78 serves to move the matrices along the assembler each time rail 44 is actuated for longitudinal movement to a position for permitting matrices to fall to the regular

4

position on rail 32. A guide 82 on rail 44 overlies and slides along the top face of bar 46, as rail 44 reciprocates longitudinally.

A coiled or helical spring 84 having one end thereof attached to a pin 86 on ear 64 and the opposite end secured to that arm 56 adjacent clip 80, yieldably holds rail 44 at one end of its longitudinal path of travel.

It is seen that the innermost marginal edge of rail 44 is normally in a position overlying rail 32 as shown in Fig. 4 and in full lines in Fig. 3. Actuation of finger 58 rotates shaft 54 to retract plate 44 away from wall 38 through arms 56 and to a position where indentations 74 receive balls 70 instead of indentations 72.

Because of the passage of pins 66 through slots 68, rail 44 is likewise moved transversely to an inoperative position where the innermost longitudinal edge of rail 44 is flush with the proximal edge of face 34. In such position of rail 44, matrices are free to fall upon the rail 32 and all matrices will be assembled in the lower or regular position.

When rail 44 is in the operative position it may also be moved temporarily to a position permitting assembling of matrices on rail 32 by shifting rail 44 longitudinally against the action of spring 84. Such shifting movement is effected by swinging an L-shaped lever 88 on its pivotal mounting 90. One end of lever 88 extends into ear 64 while the opposite end thereof overlies one end of a link 92. Link 92 is pivoted at 94 adjacent keyboard 10 and has an actuating knob 96 on its opposite end.

Lever 88 may also be swung on pivot 90 through use of a foot pedal 98 pivoted at 100. A rigidly secured, U-shaped bracket 102 receives a vertically reciprocable rod 104 having a bifurcated, uppermost end 106 embracing link 92. The lowermost end of rod 104 is pivotally secured to pedal 98. A spring 108, coiled about rod 104 within bracket 102, has the lowermost end thereof bearing against bracket 102 and its opposite end bearing against a collar 110 on rod 104. A second collar 112 on rod 104 below bracket 102 normally bears against a lock finger 114 pivotally secured to bracket 102. In such normal position, finger 114 holds spring 108 compressed and end 106 of rod 104 sufficiently clear of link 92 to permit free use of the latter in swinging lever 88 and thus shifting rail 44.

When finger 114 is swung clear of collar 112, the operator presses downwardly on pedal 98 until he desires to shift rail 44. Release of pressure on pedal 98 permits spring 108 to move rod 104 upwardly to swing link 92 and lever 88.

It is thus seen that rail 44 is movable relative to plate 42 by swinging of lever 88 and when rail 44 is moved against the action of spring 84, lug 78 will be clear of matrices emanating from throat 14. However, such longitudinal swinging movement of rail 44 is separate from transverse movement of rail 44 and plate 42. Rail 44 will retain all matrices assembled thereon while assembling thereof on rail 32 takes place. And, upon release of knob 96 or upon downward movement of pedal 98, spring 84 will carry rail 44 back to a matrix receiving position. Both the upper matrices, previously assembled on rail 44 and those assembled on rail 32 will move along the assembling elevator while additional matrices are arranged in alignment on rail 44. Each time rail 44 is moved by lever 88, clip 80 will move the matrices and spacers clear of additional matrices being fed to rail 32.

It is apparent that the operator may render rail 44 entirely inoperative by use of finger control 58, thereby casting only the upper characters of the matrix by assembling the same on rail 32. Or, through use of rail 44, all matrices may be caused to ride on rail 44 thereby casting the lower characters of the matrices. And, as a third alternate, he may cast upper and lower characters selectively as desired through utilization of either finger knob 96 or foot pedal 98.

When the rail 44 is in use, matrices are assembled directly thereupon without transfer first from another duplex rail as is the common practice. And rail 44 can be shifted entirely out of the way when regular assembling takes place. In either case the operator is assured that the matrices will fall into the position desired without jamming irrespective of the speed of operation of keys 12. The overall speed of operation has proved to have increased appreciably and through use of the simple easily accessible controls described above the operator's attention to keyboard operation is not detracted nor is concentration upon his work interrupted as in the case of usual types of assembler constructions.

Notable also is the ease in which conventional assemblers, including those not herein shown can be converted to embody the present improvements as well as the lack of expense in the conversion.

Such changes and modifications as fairly come within the spirit of this invention are manifestly contemplated hereby, and it is therefore desired to be limited only by the scope of the appended claims.

Having thus described the invention, what is claimed as new and desired to be secured by Letters Patent is:

1. An assembling elevator including a frame having a lowermost matrix receiving rail and an uppermost face provided with a cavity; a bar spaced above said face of the frame; means for securing the bar to the frame; an elongated plate beneath the bar and shiftable within said cavity on its transverse axis only; an elongated, uppermost, matrix-receiving rail member normally overlying said lowermost rail; and means mounting said uppermost rail for reciprocable movement on its longitudinal axis between the bar and the plate and relative thereto, said mounting joining the plate and the uppermost rail for shifting the latter on its transverse axis upon movement of the plate within the cavity along said transverse axis of the plate.

2. An assembling elevator including a frame having a lowermost matrix receiving rail and an uppermost face provided with a cavity; a bar spaced above said face of the frame; means for securing the bar to the frame; an elongated plate beneath the bar and shiftable within said cavity on its transverse axis only; an elongated, uppermost, matrix-receiving rail member normally overlying said lowermost rail; and means mounting said uppermost rail for reciprocable movement on its longitudinal axis between the bar and the plate and relative thereto, said mounting means joining the plate and the uppermost rail for shifting the latter on its transverse axis upon movement of the plate within the cavity along said transverse axis of the plate, said mounting means including longitudinally-extending, elongated slots formed in the rail and an upstanding pin on the plate for each slot respectively and extending thereinto.
3. An assembling elevator including a frame having a lowermost matrix receiving rail and an uppermost face provided with a cavity; a bar spaced above said face of the frame; means for securing the bar to the frame; an elongated plate beneath the bar and shiftable within said cavity on its transverse axis only; an elongated, uppermost, matrix-receiving rail member normally overlying said lowermost rail; and means mounting said uppermost rail for reciprocable movement on its longitudinal axis between the bar and the plate and relative thereto, said mounting means joining the plate and the uppermost rail for shifting the latter on its transverse axis upon movement of the plate within the cavity along said transverse axis of the plate; and resilient means carried by said frame within the cavity and bearing against said plate for yieldably holding the latter at either end of its path of travel.
